UNITED STATES PATENT OFFICE

2,559,473

LEG BRACE

Wallace L. Slodek, Sr., Nashville, Tenn.

Application January 27, 1949, Serial No. 73,135

1 Claim. (Cl. 128—80)

1

This invention relates to new and useful improvements and structural refinements in leg braces, and the principal object of the invention is to provide a device of the character herein described which is simple in construction, light in weight, durable and which may be readily adapted for use by individuals possessing various physical characteristics.

An important feature of the invention involves the provision of a pivot joint for connecting upper and lower leg straps together in such manner that they may be securely locked in a predetermined relative position, but may be expeditiously unlocked to facilitate bending of the leg at the knee.

Another feature of the invention involves the arrangement of the pivot joint and locking means in such manner that the joint automatically locks itself when the leg straps, after bending of the leg, are returned to a predetermined relative position.

With the above more important objects and features in view, and such other objects and features as may become apparent as this specification proceeds, the invention consists essentially of the arrangement and construction of parts as illustrated in the accompanying drawings, in which:

Figure 1 is a front elevational view of the invention;

Figure 2 is a side elevational view thereof;

Figure 3 is a fragmentary side elevational detail, partially broken away and showing the pivotal attachment of the foot cradle to the lower leg straps;

Figure 4 is a side elevational detail of the knee joint used in the invention;

Figure 5 is a side elevational view, similar to that shown in Figure 4, but showing the joint as being partially broken away so as to reveal its construction;

Figure 6 is a cross sectional view, taken substantially on the plane of the line 6—6 in Figure 5;

Figure 7 is a cross sectional view, taken substantially on the plane of the line 7—7 in Figure 4;

Figure 8 is a fragmentary side elevational view, similar to that shown in Figure 3 but illustrating a modified form of construction; and

Figure 9 is a cross sectional view, taken substantially on the plane of the line 9—9 in Figure 8.

Like characters of reference are employed to designate like parts in the specification and throughout the several views.

2

Referring now to the accompanying drawings in detail, the invention consists of a leg brace designated generally by the reference character 16, the same embodying in its construction, inter alia, a pair of spaced, upwardly divergent, upper leg straps 18, a pair of spaced, substantially parallel, lower leg straps 20 and a substantially U-shaped foot cradle 22.

The upper leg straps 18 are connected together 10 by suitable cross members 24, 26 and are pivotally connected to the lower leg straps 20 by a pair of pivot joints 28 which will be hereinafter described.

The lower ends of the lower leg straps 20 are 15 provided with connecting members or adapters 30 having a U-shaped cross sectional configuration so as to provide sockets wherein the lower end portions of the straps 20 may be rigidly secured by transversely extending rivets 32, and 20 it is to be noted that the sides of the adapters 30 are extended downwardly beyond the lower ends of the straps 20 so as to form a pair of spaced ears 34 between which may be pivotally mounted the upper end portions of the cradle 22 by means of a suitable pivot pin or rivet 36. The upper end portions of the cradle 22 are 25 formed with rearwardly extending projections 38 which are engageable with the lower edge of the bight portion of the members 30 when the cradle 22 is substantially horizontal, so that the cradle is effectively prevented from swinging rearwardly on the pivot 36. However, forward swinging of the cradle in the direction of the arrow 40 is facilitated, such as for example, during 30 walking.

However, in the modified embodiment of the invention illustrated in Figures 8 and 9, the projections 38 are not provided on the cradle 42, so that swinging of the cradle in both directions is possible. In other words, assuming the cradle 42 in Figures 8 and 9 to remain stationary, the leg strap 20 may swing forwardly and rearwardly as indicated at 44, 46 respectively, while in the embodiment illustrated in Figure 3 the strap 20 may swing only forwardly as indicated at 48.

Referring now to the construction of the pivot joints 28 which constitute the essence of the invention, the two joints used in the leg brace 50 are similar in construction, so that a description of one will suffice for both.

Each of the joints 28 consists of a pair of joint members 50, 52 which, like the aforementioned adapter 30, are U-shaped in cross section, whereby the lower end portion of the strap 18 may be secured in the socket provided by the U-shaped

configuration of the member 50, such as for example by suitable rivets 54. Similarly, the upper end portion of the lower leg strap 20 is secured in the socket provided by the joint member 52, by means of suitable rivets 56.

The sides of the joint members 50, 52 extend beyond the respective lower and upper ends of the straps 18, 20, and provide pairs of spaced, interfitting ears 58, 60 respectively, which are pivotally connected together by a transversely extending pin or rivet 62. By virtue of this arrangement the straps 18, 20 may be swung angularly with the movement of the leg at the knee as is exemplified at 64, 66 in Figure 2. However, it is to be noted that the interfitting bight portions of the joint members 50, 52 are in abutment as at 68 when the straps 18, 20 are longitudinally aligned, whereby the straps are prevented from swinging forwardly of the joint 28. Moreover, means are provided for releasably locking the straps 18, 20 in longitudinal alignment, these means involving the provision of a cam piece 70 which is secured between the ears 60 of the joint member 52 by being positioned substantially concentrically on the pivot pin or rivet 62. As is best shown in Figure 5, the cam piece 70 is formed in the peripheral edge thereof with a concave notch or seat 72 which is adapted to receive therein a convex detent 74 provided on a substantially L-shaped locking pawl 76. This pawl is pivotally mounted by means of a rivet 78 between the spaced sides of the joint member 50, and it is to be noted that a portion of the pawl projects outwardly from the joint member so as to constitute what may be referred to as a finger-piece 80.

A stem 82 is pivotally connected at one end thereof at 84 to the finger-piece 80 and is slideable in a guide 86 secured by welding, or the like, to the joint member 50, a suitable compression spring being provided on the stem 82 and bearing against the guide 86 and the finger-piece 80, whereby the detent 74 is urged in engagement with the periphery of the cam piece 70, particularly in engagement with the seat 72.

Accordingly, the engagement of the detent 74 with the seat 72 will effectively lock the leg straps 18, 20 in longitudinal alignment, but by simply actuating the finger-piece 80 in the direction of the arrow 90 (see Figures 4 and 5) the spring 88 will be compressed while the stem 82 slides through the guide 86, and the detent 74 will be disengaged from the seat 72, so that the straps 18, 20 may be swung, one relative to the other, as necessitated by the bending of the leg at the knee. However, after the finger-piece 80 is released and the leg is straightened, the spring 88 will force the detent 74 into the seat 72, thus automatically locking the straps 18, 20 in their normal, longitudinally aligned positions as will be clearly apparent.

It may be explained that the particular concave configuration of the seat 72 and the complementarily convex configuration of the detent

74 facilitates efficient engagement and disengagement of the detent upon manipulation of the finger-piece 80. It may be also explained that the locking mechanism 70, 76, 82 and 88 may be provided on both joints 28 of the leg brace, or only on one joint, as desired.

Attention is also directed to the aforementioned pins or rivets 62, these being provided with relatively large heads at one end, and carrying at their remaining ends relatively large washers 92, so that these heads and washers substantially reinforce the joints by abutting the interfitting ears 58, 60.

It is believed that the advantages and use of the invention will be clearly apparent from the foregoing disclosure and accordingly, further description thereof at this point is deemed unnecessary.

While in the foregoing there has been shown and described the preferred embodiment of this invention, it is to be understood that minor changes in the details of construction and arrangement of parts may be resorted to without departing from the spirit and scope of the invention as claimed.

Having described the invention, what is claimed as new is:

In a leg brace, the combination of upper and lower straps, upper and lower joint members each having a substantially U-shaped socket, end portions of said straps being secured in the respective sockets, a pivot pin connecting said members together, a cam secured on said pin in the socket of the lower joint member and provided in its upper edge portion with a concave depression constituting a seat, a pawl pivotally mounted in the socket of the upper member, a convex detent provided on said pawl and engaging said seat, an apertured guide secured to said upper member above said pawl, a stem pivoted at one end thereof to said pawl and slideable in the aperture of said guide and, a compression spring provided on said stem and bearing against said pawl and said guide whereby said detent is urged in said seat to lock said members and straps in a predetermined relative position, an end portion of said pawl projecting outwardly from the associated socket and constituting a finger-piece whereby said pawl may be actuated against the resiliency of said spring to disengage said detent from said seat.

WALLACE L. SLODEK, SR.
